(57) **CLAIM**

The ornamental design for a pair of vent plugs for motorcycle fairings, as shown and described.

DESCRIPTION

FIG. 1 is a front elevational view of a pair of vent plugs for motorcycle fairings, shown in position of use on a motorcycle, which is shown in broken lines for purposes only and forms no part of the claimed design;

FIG. 2 is an enlarged front elevational view of the right vent plug of the pair of vent plugs for motorcycle fairings;

FIG. 3 is a left side elevational view of FIG. 2;

FIG. 4 is a right side elevational view of FIG. 2;

FIG. 5 is a rear elevational view of FIG. 2;

FIG. 6 is a right end elevational view of FIG. 2; and,

FIG. 7 is a left end elevational view of FIG. 2.

The left vent plug of the pair of vent plugs for motorcycle fairings is a mirror image of the right vent plug.
